EGG CADDY

Rex G. Moore, Jackson, Miss.
(213 Savanna St., Hinds, Miss. 39212)

Filed Aug. 14, 1967, Ser. No. 8,258

Term of patent 14 years

(Cl. D44—10)

I claim:

The ornamental design for an egg caddy, as shown.
